United States Patent Office.

JOHN F. FORD, OF BOSTON, MASSACHUSETTS.

Letters Patent No. 77,603, dated May 5, 1868; antedated April 28, 1868.

WINDOW SAFETY-GUARD.

The Schedule referred to in these Letters Patent and making part of the same.

TO ALL PERSONS TO WHOM THESE PRESENTS MAY COME:

Be it known that I, JOHN F. FORD, of Boston, in the county of Suffolk, and State of Massachusetts, have invented an Improved Safety-Guard for Windows; and do hereby declare the same to be fully described in the following specification, and represented in the accompanying drawings, of which—

Figure 1 is a side elevation,

Figure 2 a top view, and

Figure 3 a vertical and longitudinal section of it.

In such drawings, A and B are two bars, arranged parallel to each other, and provided on their outer sides with teeth or spurs, as shown at *a a*.

Each of such bars has three projections *b c b*, extending from its inner surface, each of such projections being socketed axially; each of the middle projections of the two bars containing in its socket a helical spring, *d*, and is to receive one end of a round bar, C, which may be clamped to one of the projections *c* by a clamp-screw, *e*, screwed laterally into it.

Other round bars D, arranged parallel to the bar C, and with respect to it, in manner as represented, have male screws *f g* on their opposite ends, the pitch of one being the reverse of that of the other of each of such bars. These screws are to screw into the socketed projections *b b* of the two bars A B.

By revolving the upper and lower bars D D, the two bars A B may be made to either approach or recede from each other, the same being to enable the guard to be fitted or adjusted to a window-frame, and be fastened in place therein, by forcing the spurs of the guard into the opposite sides of the frame.

The purpose of the guard is to prevent young children from falling out of the window.

I claim, as my invention, the window-guard, as composed of the bars A B C D, arranged and connected by screws, and having spurs, substantially as described.

I also claim the combination and arrangement of the springs *d d* in the sockets of the middle projections of the bars A B, with such bars and their spurs, and the bars C D applied to the bars A B, substantially as specified.

JOHN F. FORD.
